(57) **CLAIM**

The ornamental design for a portion of a counterweight for construction machine, as shown and described.

DESCRIPTION

FIG. 1 is a front, top and right side perspective view of a portion of a counterweight for construction machine according to the design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof; and,

FIG. 8 is an enlarged view of the portion shown in BOX 8 in FIG. 2.

The broken lines show a portion of a counterweight for construction machine that form no part of the claimed design.
